UNITED STATES PATENT OFFICE.

ALFRED P. HANTSCH, OF NEW BRUNSWICK, NEW JERSEY.

PLATE ENVELOPE.

1,423,420.

Specification of Letters Patent.

Patented July 18, 1922.

Application filed June 4, 1920. Serial No. 386,434.

To all whom it may concern:

Be it known that I, ALFRED P. HANTSCH, a citizen of the United States, residing at New Brunswick, in the county of Middlesex and State of New Jersey, have invented new and useful Improvements in Plate Envelopes, of which the following is a specification.

This invention relates to improvements 10 in plate holders and one of the objects is to produce a cheap and efficient device of this nature.

Other objects will appear hereinafter.

All of these objects are accomplished by 15 means hereinafter described and claimed and which are fully illustrated in the accompanying drawings consisting of one sheet, in which:—

Figure 1 is a plan view of the plate holder blank.

Figure 2 is a perspective view illustrating the method of folding the holder blank about the plate.

Figure 3 is a view of a more nearly folded condition of the blank.

Figure 4 is a view of the completely folded blank.

Like characters of reference refer to like parts throughout the several views.

This invention contemplates the providing 30 of a plate envelope in which the plate is wrapped in a piece of light excluding material cut and folded so that by pulling on a tab, the plate may be exposed when in the camera so as to be ready for taking a picture upon operating the shutter.

The photographic plate is represented at 11 and I purpose to have this a plate of the style commonly used in taking "tin types" 40 although it is to be understood that it may be of glass or gelatine. A plate holder blank is shown in Figure 1 and comprises a strip of light-proof material which is provided with a plate-exposing aperture 12 and is adapted to be folded at 13 and 14 in lines 45 parallel with the major axis of the blank and at 15, 16, 17 and 18 transversely of the major axis of the blank for a purpose now to be set forth. As shown in Figure 2, the 50 plate 11 is placed on the plate holding blank

between lines 15 and 16 with the sensitized side up; then the strip is doubled at 16 over the sensitized face and bent back on itself at 17; the face is then folded up at 15 and edges are bent at 13 and 14 so as to protect 55 the edges of the plate and hold the entire structure in intimate relation. The strip is then bent at right angles at 18 to form an operating tab 19. This plate is now protected for day light loading.

In use the tab 19 is exposed from the camera after loading, and when it is desired to take a picture, the tab 19 is pulled until the folded portion of the paper or plate holder has been drawn up from in front of the 65 plate. Exposure may then be made in the usual way.

While I have described what I deem to be the most desirable embodiment of my invention, it is obvious that many of the details 70 may be varied without in any way departing from the spirit of my invention; and I therefore do not limit myself to the exact details of construction herein set forth nor to anything less than the whole of my invention limited only by the appended claims.

What I claim as new and desire to secure by Letters-Patent is:

1. A plate carrying member which comprises an apertured portion, a portion to back a plate, a portion adapted to be bent upon itself to cover the face of a plate, a manipulative tab, and portions at the margins of said apertured portions and adapted 80 to fold about a plate so as to hold the plate and backing portion and the face-covering portions in intimate association.

2. A plate envelope comprising a single piece of flexible, light-proof material having 90 an apertured face portion, a plate-backing portion, a plate-covering portion interposed between the first and second portions for covering the face of a plate, and a tab portion manipulative for removing said plate-covering portion from its covering position.

3. A plate envelope comprising a single piece of flexible light-proof material folded so as to entirely enclose a plate and having one portion extended into a manipulative 100

element for effecting an unfolding of a portion of the envelope to expose the enclosed plate when desired.

4. A plate envelope comprising a single piece of flexible light-proof material folded so as to entirely enclose a plate and having an apertured portion to be disposed in front of the plate, a portion normally mask-

ing the aperture in the first said portion, and a manipulative portion operable for removing the masking portion from masking relation with said aperture.

In testimony whereof I have affixed my signature.

ALFRED P. HANTSCH.
